(57) **CLAIM**

The ornamental design for an expandable garbage container as shown and described.

DESCRIPTION

FIG. 1 is an isometric view of an expandable garbage container showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is another isometric view of my new design in an alternate configuration.
